United States Patent Office

Des. 228,743
Patented Oct. 23, 1973

228,743

CLOSURE OR SIMILAR ARTICLE

Wayne E. Maw, Gladstone, Mo., assignor to Phillips Petroleum Company

Filed Sept. 20, 1971, Ser. No. 182,308

Term of patent 14 years

Int. Cl. D9—99

U.S. Cl. D9—254

FIG. 1

FIG. 3

FIG. 1 is a top plan view of a closure or similar article showing my new design;

FIG. 2 is a side elevational view, partly in section on the line 2—2 in FIG. 1; and

FIG. 3 is a perspective view thereof.

I claim:

The ornamental design for a closure or similar article, as shown and described.
